RINGLET HAIR CURLER

Filed Sept. 25, 1939

UNITED STATES PATENT OFFICE

2,212,569

RINGLET HAIR CURLER

Zack Lemley, Denver, Colo.

Application September 25, 1939, Serial No. 296,430

6 Claims. (Cl. 132—40)

This invention relates to a hair curler and has for its principal object the provision of a neat, simple, easily used and highly efficient device which can be expertly used by anyone for forming the modern flat ringlets in the hair.

Curlers at present on the market produce long sausage-shaped curls. The modern tendency in hair dressing is to employ thin spiral curls or ringlets which lie flat against the scalp. It is for this particular purpose that this invention is designed.

Other objects and advantages reside in the detail construction of the invention, which is designed for simplicity, economy, and efficiency.

These will become more apparent from the following description.

In the following detailed description of the invention reference is had to the accompanying drawing which forms a part hereof. Like numerals refer to like parts in all views of the drawing and throughout the description.

In the drawing:

Fig. 1 illustrates the improved curler in use.

Fig. 2 is a perspective view of one form of the improved ringlet curler, illustrating it in the open position.

Fig. 3 is a perspective view thereof illustrating the curler in the closed position.

Fig. 4 is a cross section through the curler of Fig. 3.

Fig. 5 is an elevational view of the curler as it would appear at the start of a curling operation.

Fig. 6 is a similar view illustrating the curler at the completion of the curling operation.

Fig. 7 is a perspective view looking toward the outer face of the curler.

Fig. 8 is a perspective view of an alternate form of curler.

Fig. 9 is an outer face view of the alternate form of Fig. 8.

Fig. 10 is a cross section through the alternate form.

Fig. 11 is an edge view thereof.

Fig. 12 is a detail view illustrating the attachment clip employed with the alternate form.

The form of the invention illustrated in Figs. 1 to 7 comprises a disc 13 from which a conical stud 14 axially projects. The diameter of the stud 14 adjacent the disc 13 is less than its diameter at the free extremity. A hinged clamp 15 is hinged to the inner face of the disc 13 upon a suitable hinge pin 16. The extremity of the hinge clamp terminates in a locking tongue or snap 17 which snaps into a depression in the

extremity of the stud portion 14 to hold the clamp 15 closed, as shown in Fig. 3. The clamp 15 is for clamping the tip extremity of a strand or lock of hair to the stud member 14.

A second clamp is provided for clamping the root extremity of the lock of hair in place. The latter consists of a length of spring wire 18 bent at one extremity to form a finger clip 19. The other extremity thereof is formed to conform to the shape of the edge of the disc 13 and the side of the stud portion 14 to form a wire clamp 20.

The wire 18 is clamped against the face of the disc by means of a clamping plunger 21 through which it passes. The plunger 21 is constantly pulled inwardly by means of a compression spring 22 acting against a head 23. This constantly causes the plunger to frictionally engage the wire 18 to hold it in any present position therein. The wire 18 and the plunger 21 can be freely rotated around the disc portion 13 to any desired position thereon. When this position is reached, the wire is forced radially inward to clamp the hair against the stud. When forced inwardly, it engages one of a series of peripheral notches 24 in the inner face of the disc portion 13 to prevent further rotation.

In use, the extremity of the chosen strand of hair is clamped in place on the stud 14 by means of the clamp 15, as shown in Fig. 5. The entire device is then rotated with the free extremity of the stud against the scalp to coil the hair around the stud. When the strand has been completely coiled thereon, the wire 18 is rotated to a position over the root extremity of the hair and is then forced inwardly against the coiled curl to hold the curler in place on the head, as shown in Fig. 1. The wire holds the curl in place regardless of the amount of hair thereon since the plunger 21 will clamp it in any position. The curler cannot uncoil from the hair since the notches 24 prevent the clamp 20 from rotating.

The alternate form of the invention, shown in Figs. 8 to 12, inclusive, is used in the same manner and for the same purpose as the first described form.

The alternate form consists of a similar conical stud 25 from which a semi-circular flange 26 projects. A second semi-circular flange 27 is hinged to the flange 26 upon a suitable hinge pin 28 and the two together form a complete circular flange. A semi-conical shell 29 projects from the hinged flange 27 and, when the latter is in alignment with the flange 26, the shell 29

snugly engages one-half the surface of the stud 25.

The shell is constantly urged to the closed position by means of a wire spring 30 carried on the hinge pin 28.

With this form a separate spring clip 31 is provided. The clip is shaped to receive the flange portions of the device and to lie along the stud portion thereof, as shown in Fig. 11. This 10 form of the device is used similarly to the first form. The tip extremity of a strand of hair is placed on the stud 25 and clamped thereon by means of the shell 29. The device is then rotated to coil the hair until the root extremity has been 15 reached. The clip 31 is now slipped over the scalp extremity of the hair and is clamped to the stud to hold the device on the hair with the stud extremity against the scalp similar to the first form.

20 The faces of the flange portions 26 and 27 are provided with a concentric series of grooves 32. The extremity of the clip 31 is corrugated, as shown at 33, and the tip thereof is turned inwardly, as shown at 34, so as to engage in any 25 of the grooves at any position that the clip may be placed to hold the latter in place at any desired diametric or circumferential position.

While a specific form of the improvement has been described and illustrated herein, it is desired to be understood that the same may be varied, within the scope of the appended claims, without departing from the spirit of the invention.

Having thus described the invention, what is 35 claimed and desired secured by Letters Patent is:

1. A hair ringlet curling device comprising: a circular disc; a stud member projecting axially from one face of said disc; a resiliently actuated 40 clamp for clamping the tip extremity of a strand of hair on said stud member; and a slideable clamping member for clamping a coil of hair on said stud member.

2. A hair ringlet curling device comprising: a circular disc; a stud member projecting axially 45 from one face of said disc; a resiliently actuated clamp for clamping the tip extremity of a strand of hair on said stud member; and a second

clamping member for securing a coil of hair on said stud, said second member being rotatable about said stud; and means for locking said second member at any desired diametric position.

3. A hair ringlet curling device comprising: a circular disc; a stud member projecting axially from one face of said disc; a resiliently actuated clamp for clamping the tip extremity of a strand of hair on said stud member; a slideable clamping member for clamping a coil of hair on said stud member; and means for causing said latter clamping member to frictionally engage said disc to retain its position thereon.

4. A hair ringlet curler comprising: a relatively short stud for receiving a coil of hair; a semi-circular flange projecting about one extremity of said stud; a hinged semi-circular flange hingedly attached to the first flange to form a complete circular flange; a shell portion projecting from the hinged flange shaped to fit about said stud; and spring means for urging said flanges into alignment with each other.

5. A hair ringlet curler comprising: a relatively short stud for receiving a coil of hair; a semi-circular flange projecting about one extremity of said stud; a hinged semi-circular flange hingedly attached to the first flange to form a complete circular flange; a shell portion projecting from the hinged flange shaped to fit about said stud; and spring means for urging said flanges into alignment with each other, said stud having a less diameter adjacent said flange than at its free extremity, said shell being shaped to enclose substantially one-half of said stud.

6. A hair ringlet curler comprising: a relatively short stud for receiving a coil of hair; a semi-circular flange projecting about one extremity of said stud; a hinged semi-circular flange hingedly attached to the first flange to form a complete circular flange; a shell portion projecting from the hinged flange shaped to fit about said stud; spring means for urging said flanges into alignment with each other; and a 45 spring clip member engaging said flange for holding a coil of hair on said stud.

ZACK LEMLEY.
